FRED HERBERT, OF BIRTLEY, ENGLAND.

MACHINE FOR MAKING SAND MOLDS.

No. 877,999.

Specification of Letters Patent.

Patented Feb. 4, 1908.

Application filed December 26, 1906. Serial No. 349,539.

To all whom it may concern:

Be it known that I, FRED HERBERT, a subject of the King of Great Britain, residing at Birtley, county of Durham, England, 5 have made a certain new and useful Invention in Machines for Making Sand Molds, of which the following is a specification.

The invention relates to machines for making sand molds.

10 The object of the invention is to provide a machine which is simple in construction, and efficient in operation, for forming sand molds.

A further object is to provide a machine 15 of the character referred to, for making molds of different sizes.

Other objects of the invention will appear more fully hereinafter.

The invention consists substantially in the 20 construction, combination, location and arrangement of parts, all as will be more fully hereinafter set forth, as shown in the accompanying drawings, and finally pointed out in the appended claims.

25 Referring to the accompanying drawings, and to the various views and reference signs appearing thereon,—Figure 1 is a view in top plan of a machine embodying my invention. Fig. 2 is a broken view in vertical 30 longitudinal section showing two sets of sand mold forming devices, one set being shown in retracted position and the other set being shown in advanced position.

In a plant equipped for forming sand 35 molds, and in order to supply varying sizes of molds, it is desirable to provide means whereby the varying sizes of molds may be formed and produced expeditiously, and with the greatest economy of space. Machines of this character are usually large, 40 cumbersome and expensive and each machine requires a considerable floor space, thereby rendering it difficult and expensive to equip a plant with a separate machine 45 for each size of pipe mold to be produced. Again, in the construction of each mold it is exceedingly important to pack or ram the sand uniformly throughout, so as to produce a homogeneous product, thereby avoiding 50 the possibility of spoiling the pipe to be produced or cast, through inequalities of contraction of the metal due to inequalities in the density of the mold. In securing the best results it is also essential that the mold 55 be formed in absolutely true alinement from end to end. This is exceedingly difficult to

attain especially in the case of molds of small diameter and great length.

It is among the special purposes of the present invention to provide a machine, 60 which, while occupying the same, or very little more than the space necessary to accommodate a single machine for large size molds, is capable of forming a plurality of molds of small diameter.

It is also among the special purposes of the present invention to provide a machine for forming molds of small diameter and of great length with the same degree of uniformity of density of compactness throughout as is necessary in forming molds for pipes of larger diameters, and wherein the same accuracy in alinement is secured, and wherein the sockets and spigots are formed with the same facility and efficiency as in the case 75 of larger sized molds.

In carrying out my invention I employ a main casing A, in which I arrange a base support B, for a plurality of stationary vertical hydraulic cylinders C, of a length as 80 great or greater than the length of the molds to be formed to each of which may be supplied an operating medium at a point adjacent its lower end, as, for instance, through the port D. In practice, and as shown, but 85 not necessarily, the port D, of each cylinder is located below a partition or division plate E, of the cylinder, and which partition or cylinder has a central opening F, to admit the operating medium thereto, to the portion 90 of the cylinder above such plate or partition. Working within each cylinder is a plunger G. Each piston at its upper end is formed with a seat or socket to receive the end of a pattern or rammer, H, of extended length. 95 The length of such pattern or rammer being greater than the length of the mold to be formed. The lower end of the pattern or rammer H, is secured in any suitable or convenient manner in the socket or seat in the 100 upper end of the piston G, as, for instance, by means of a key or wedge J, whereby such pattern or rammer may be readily detached and removed for replacement. In this manner varying sizes of patterns or rammers may 105 be employed in connection with each piston or plunger. Ordinarily, however, and as shown, I propose to employ varying sizes of patterns or rammers for the respective plungers or pistons, thereby enabling the 110 same machine to produce varying sizes of molds, within a desirable range of sizes of

pipes required, without the necessity of removing or replacing individual patterns or rammers.

Supported upon the upper end of the main casing is an auxiliary casing K, upon which is received, supported and centered the flask L, in which the mold is formed. Reference sign M, designates a sleeve of extended length, as distinguished from a ring. This sleeve is arranged to be received within the auxiliary casing K, and is shaped at its upper end, as indicated at N, to form the socket pattern for the mold. At its lower end the sleeve M is provided with a flange O, through which are tapped adjusting screws P, adapted to form adjustable stops for limiting the upward movement of such sleeve, said stops abutting against the under side of the base of the auxiliary casing when said sleeve is raised sufficiently. The sleeve M, is supported, when in its retracted position, by pins or supports R, adapted to be inserted through any one of a series of holes S, in auxiliary casing K, whereby the normal height of the socket pattern portion of sleeve M, when in its retracted position may be adjustably regulated, thereby regulating and adjusting the position of the socket pattern part of the sleeve with reference to the lower end of the flask in which said pattern is received, and hence also regulating and controlling the quantity of sand or other composition required to form the socket end of the mold. The main pattern H, is arranged to pass through and is closely fitted to the bore of sleeve M, and said sleeve, as well as the flask, is supported and arranged in absolute and true alinement with the line of movement of the main pattern H. The upper end of the main pattern is slightly tapering for a considerable distance, as indicated at T, and is provided at the extremity thereof with a seat or shoulder U, upon which is received and centered the lower end of a tube V, which serves as a measuring tool for measuring and controlling the amount of sand or other composition supplied to the flask to form the mold.

It will be readily understood that as the main pattern is raised through the flask in the performance of its work of ramming, compressing, and smoothing the bore of the mold, this measuring tube is gradually and correspondingly displaced endwise through the upper end of the flask, and finally, when the advancing end of the main pattern emerges above the upper end of the flask the measuring tool will have entirely completed its work and is then removed. Upon the projecting end of the main pattern a spigot and gate forming pattern, indicated at W, is then secured and the stroke of the main pattern is reversed, thereby causing such spigot and gate pattern to be carried down to perform its work of forming the upper end of the

mold. When this work is completed the spigot pattern is removed and the main pattern withdrawn to its initial retracted position to permit the flask, with its completed mold, to be removed. The measuring tool may be centered in the upper end of the flask, and guided and held in proper centered relation in any suitable or convenient manner, as for instance, by means of a spider indicated at A'.
75

The operation is exceedingly simple. When a mold for a pipe of the desired diameter is to be made the main pattern H, of the desired size is raised through the sleeve end, until the tapering end T, of such pattern just projects quite through the upper end of the sleeve M, extending into the flask L, as clearly shown at the left of Fig. 2, the raising of the pattern being effected by admitting operating medium to the cylinder C, through port D, and below the lower end of the plunger G, thereby causing the plunger to move longitudinally through the cylinder cap, carrying the main pattern with it. With the main pattern in the position shown at the left of Fig. 2, the measuring tool V, is inserted through the upper end of the flask and is received, supported and centered at its lower end upon the shoulder U, on the end of the main pattern, and is properly centered at its upper end within the flask. The sand to form the mold is then introduced to the flask and into the space bounded by the inner surface of the flask, the inner wall of the auxiliary casing, at the upper end thereof, the exterior surface of the socket pattern portion of the sleeve M, and the exterior surfaces of the main pattern and the measuring tool. In this manner the size or diameter of the measuring tool determines or measures the space into which the sand to form the mold is delivered, thereby measuring the quantity of the sand required. Ordinarily, the tapering end of the main pattern includes practically the entire extent of that portion of the upper end thereof which extends into the flask when the sand or other composition is introduced to the flask. When the sand has been introduced into the flask, as above explained, the power medium is again admitted to the cylinder C, and the main pattern H, is advanced longitudinally through the sleeve M, and flask L, being guided with absolutely true alinement by such sleeve, and also by the mold as it is formed. The upper long tapering advancing end of the main pattern constitutes the rammer and effects the desired ramming and compression of the sand within the flask, the bore of the mold thus compacted and compressed, being smoothed and ironed out by the cylindrical portion of the main pattern, below the ramming end thereof, as such portion of the main pattern advances through the compressed sand, and such bore also affords a guiding support for 100

- maintaining absolute alinement of the pattern in its advancing movement. The sleeve M, also affords a most efficient guide for the main pattern, and herein lies the importance and value of employing a sleeve of extended length, rather than a mere ring, and when I refer to this element of the machine as a sleeve, I desire to be understood as making this distinction. As the main pattern approaches the upper limit of its stroke the upper end of the plunger G, abuts against the lower end of the sleeve M, and thereafter the sleeve and main pattern advance together, the socket pattern part N, of the sleeve forming, ramming and compacting the sand at the lower end of the mold, to form the socket end thereof. The extent of the advancing movement of the sleeve being adjusted and regulated by the set screws P.
- By the time the sleeve M, has completed its upper movement, the upper end of the main pattern will have advanced entirely through the flask, thereby forcing out the measuring tool, which is then removed and the spigot or gate pattern W, is secured in place on the end of the main pattern. The stroke of the main pattern is then reversed and the spigot pattern is carried down upon the upper end of the mold, and flask to properly perform its work. This downward movement is then temporarily interrupted to permit the spigot pattern to be removed. The main pattern is then lowered to its initial position, permitting the flask containing the completed mold to be removed and replaced by another flask. The apparatus is then ready for another operation.
- It will be seen that the use of a long cylinder C, with the plunger or piston G, operating therein, the sleeve M, of extended length through which the main pattern operates, and the bore of the forming mold, all contribute to maintain absolute and true alinement of the main pattern while performing its work, thereby insuring an absolutely true mold, and in these features resides an important characteristic of my present invention. It will also be seen that each mold, whether of smaller or larger diameter is packed or rammed to uniform density throughout, including the socket and spigot ends thereof. It will also be seen that I provide an exceedingly simple and efficient construction where-in I embody in a single main casing means for producing molds of different diameters, and this is particularly important and desirable in the case of plants for making molds for long pipes of small diameter, enabling such molds to be made in varieties of sizes and as readily and easily, and with as great facility and efficiency, as in the case of larger molds, and entirely by machinery, and with practically no greater requirement for floor space than is necessary for a single machine. It will also be seen that I am enabled to prolong the length of the operating cylinder to the top plate of the main casing and closely adjacent to the lower end of the sleeve M, thereby requiring the plunger or piston G, to emerge only a short distance from the cylinder in order to engage and raise the sleeve M to the limit of its upward stroke to enable the socket pattern formed thereon to perform its work, and hence enabling the cylinder C, to serve efficiently as a guide to maintain the true and accurate alinement of the parts throughout the entire stroke of the piston.
- Having now set forth the object and nature of my invention and a construction embodying the principles thereof, and having described such construction, its purpose, function and mode of operation, what I claim as new and useful and of my own invention, and desire to secure by Letters Patent is:—
1. In a machine for forming sand molds, the combination with a main casing, of a stationary cylinder arranged therein and adapted to receive an operating medium, a piston operating in said cylinder and having a socket or seat in the end thereof, a main pattern having its lower end stepped and secured in said socket or seat, the upper end of said main pattern being tapered and provided with a shoulder, an auxiliary casing, a sleeve of extended length, supported in said auxiliary casing and through which said pattern operates; a flask supported upon said auxiliary casing, to receive the pattern therethrough, and a measuring tool supported upon the shoulder at the upper end of said pattern.
2. In a machine for forming sand molds, the combination with a stationary cylinder and a piston plunger operating therein, said piston plunger having a seat in the upper end thereof, of a pattern having its lower end stepped and secured in said seat, the upper end of said pattern being tapered and provided with a shoulder forming a seat, a measuring tool supported and centered upon said shoulder, a flask arranged to receive the pattern and the measuring tool longitudinally through the bore thereof, a sleeve of extended length supported below the flask in position to receive the pattern therethrough, said sleeve having a socket pattern at its upper end, and means for adjusting the position of the sleeve with reference to its support, said sleeve arranged to be engaged by the piston whereby it is advanced to its work.
3. In a machine for making sand molds, the combination with a cylinder and plunger, a pattern carried by the plunger, and a flask, of a sleeve of extended length, arranged below the flask and through which the pattern operates, means for adjustably supporting said sleeve with reference to the flask, said

sleeve adapted to be engaged by the plunger whereby it is advanced endwise towards the flask, and set screws for adjustably regulating the extent of such advancing movement, 5 said sleeve carrying a socket pattern at its upper end.

4. In a machine for making sand molds, the combination with a cylinder, a plunger operating therein, a pattern stepped and removably secured in a seat formed in the end of the plunger, and having a supporting shoulder at its upper end, a measuring tool adapted to be supported and carried by said shoulder, and a flask, of an auxiliary casing, 10 a sleeve of extended length adjustably supported therein for movement endwise towards the flask, said sleeve formed with a socket pattern at its upper end, the plunger adapted to engage the lower end of said sleeve to advance the same.

5. In a machine for making sand molds, the combination with a cylinder, a plunger operating therein, and having a seat in the end thereof, a pattern having its lower end received and secured in said seat, a measuring tool supported and centered upon the upper end of the pattern, and a flask, the upper end of said pattern being tapered, of a casing supporting said flask, a sleeve of extended 25 length arranged within said casing for endwise movement therein, said pattern operating through said sleeve, the lower end of said sleeve adapted to be engaged by the end of the plunger whereby said sleeve is moved 30 endwise, means for adjustably supporting said sleeve, a socket pattern carried by the upper end of the sleeve, and means for adjustably limiting the endwise movement of the sleeve.

40 6. In a machine for making sand molds, a main casing having a base plate, a plurality of stationary cylinders arranged in said casing and supported upon said base plate, a

plunger operating in each cylinder, each plunger having a seat in the end thereof and 45 a pattern supported in the seat in the end of each plunger, said patterns varying from each other in diameter.

7. In a machine for making sand molds, a main casing, a base plate arranged therein, a plurality of cylinders mounted on said base plate, a plunger operating in each cylinder, a pattern carried by each plunger, a flask through which each pattern operates, and means for guiding each pattern, said patterns varying from each other in diameter.

8. In a machine for forming sand molds, the combination with a stationary cylinder of a length as great as the length of the mold to be formed, a plunger operating in said cylinder, and a pattern or rammer removably secured to the end of said plunger, said pattern or rammer being of greater length than the length of the mold to be formed, of a flask, means for supporting and centering 65 said flask in axial alinement with said pattern or rammer, a sleeve of extended length surrounding the pattern or rammer, and shaped at its upper end to form the socket end of the mold, means for adjustably supporting said sleeve, a measuring tool centered and removably supported upon the upper end of the pattern, means for centering and guiding said tool in said flask, and a spigot pattern adapted to be detachably secured to the end of the first mentioned pattern.

In testimony whereof I have signed my name to this specification, in the presence of two subscribing witnesses, on this seventh 80 day of December A. D. 1906.

FRED HERBERT.
